ATTORNEY.

UNITED STATES PATENT OFFICE.

WILLIAM DE GOEY, OF PROVIDENCE, RHODE ISLAND.

DESIGN FOR A DISH OR SIMILAR ARTICLE.

40,367.

Specification for Design.

Patented Nov. 23, 1909.

Application filed August 30, 1909. Serial No. 515,372. Term of patent 3½ years.

To all whom it may concern:

Be it known that I, WILLIAM DE GOEY, a citizen of the United States, residing at Providence, in the county of Providence and State of Rhode Island, have invented a new, original, and ornamental Design for a Dish or a Similar Article, of which the following is a specification, reference being had to the accompanying drawing, forming a part thereof.

The figure is a plan view of a dish, showing my new design.

I claim:

The ornamental design for a dish or a similar article, as shown.

WILLIAM DE GOEY.
